UNITED STATES PATENT OFFICE

111,067

DESIGN FOR A TEXTILE FABRIC

William Cohen, New York, N. Y.

Application June 9, 1938, Serial No. 77,685

Term of patent 3½ years

To all whom it may concern:

Be it known that I, William Cohen, a citizen of the United States of America, residing in New York city, in the Borough of Manhattan, county and State of New York, have invented a new, original, and ornamental Design for a Textile Fabric, of which the following is a specification, reference being had to the accompanying drawing, forming part thereof, wherein,

The figure is a plan view of a piece of textile fabric showing my new design.

The design is characterized by a series of spaced apart contrastingly colored superimposed stripes, the solid colored stripes being separated by matching five-colored stripes arranged on a sheer background, as shown.

I claim:

The ornamental design for a textile fabric, substantially as shown and described.

WILLIAM COHEN.
